UNITED STATES PATENT OFFICE.

CHARLES E. WAREAM, OF CINCINNATI, OHIO, ASSIGNOR TO THE AMERICAN LAUNDRY MACHINERY COMPANY, OF CINCINNATI, OHIO, A CORPORATION OF OHIO.

GARMENT PRESS.

Original application filed December 20, 1920, Serial No. 432,149. Divided and this application filed August 24, 1922. Serial No. 584,036.

To all whom it may concern:

Be it known that CHARLES E. WAREAM, a citizen of the United States, residing at Cincinnati, in the county of Hamilton and State 5 of Ohio, has invented certain new and useful Improvements in Garment Presses, of which the following is a specification.

This invention relates to garment presses, and is a division of my co-pending application 10 for garment presses, filed Dec. 20, 1920, Serial No. 432,149.

The object of the present invention is to provide an improved press embodying an improved arrangement of fluid pressure actuating devices for one of the pressing members, said devices being of simple construction and readily controlled, and including a fluid pressure cylinder so arranged as to enable the water of condensation to be readily 20 drained off or carried away without interfering with the operation of the power cylinder.

Further objects of the invention are in part obvious and in part will appear more in 25 detail hereinafter.

The single figure in the drawing is a sectional elevation of a press embodying my invention.

The machine shown in the drawings comprises a suitable frame including a hollow base 1, side pillars 2 and a stationary cross head 3, a part of which is hollowed out to form the chamber 4 of the stationary upper pressing member or head 5. The lower or 30 pressing surface of said head co-operates with the padding 6 on the lower pressing member or bed 7 carried by a standard 8 on a frame 9 which is provided with a surrounding pan shaped shield 10, the front 35 portion of which may be padded, shaped or otherwise formed as at 11, to receive the knee of the operator and which serves to protect the garment or article being operated upon from contacting with the mechanism of the 40 press. Said frame 9 is also provided with a depending post 12 for actuation upwardly by 45 the press closing means.

The particular improvement covered by this divisional application relates to the 50 fluid pressure actuating mechanism for elevating the lower pressing member. As illustrated, the stationary frame 1 has secured thereto a hollow cylinder 13 provided with an inlet and outlet channel 14 and enlarged

at its upper end to form an annular chamber 55 15 below which is an annularly extending channel 16 communicating with an outlet pipe 17 leading to the sewer or other discharge point. In said cylinder is a piston 18 having a suitable cup washer 19 on its bottom, and the stem 20 of which extends through the cap 21 and packing 22, so that its upper end lies beneath the depending post 12 when the bed is in its rear position in registration with the head. Fluid pressure is 60 applied to said cylinder through the channel 14 for elevating the piston and thereby pushing the padded bed 7 up against the head 5. The chamber 15 is hollowed out to such size 65 that when the piston is in its uppermost position the volume of the hollow space in said chamber surrounding the piston will be at least equal to the volume of the space above the piston and around its stem below the channel 16 when the piston is in its lower position. Therefore, any water of condensation 70 that may leak past the piston or collect in the space above it is inevitably carried up to the channel 16 and thereby permitted to flow away without creating back pressure 75 80 and opposing effective piston operation.

The controlling valve mechanism 23 for the steam or fluid pressure supply may be of any suitable form, the valves here being operated by treadles 24 and 25. The drawings show the same valve arrangement illustrated in my prior application for garment press, filed Feb. 16, 1920, Serial No. 359,127, to which reference may be had for a more 85 complete description.

What I claim is:

1. In a device of the class described, the combination of a fluid pressure controlling cylinder, a piston movable therein, and means for supplying fluid pressure to said cylinder, said cylinder having a main piston guiding portion and an enlarged portion at the upper end of said main guiding portion, said enlarged portion forming a condensation receiving chamber, the capacity of said 100 chamber being as great as the capacity of the chamber within the main piston guiding portion between the top of said main guiding portion and the upper face of the piston when said piston is in its lowermost 105 position.

2. In a device of the class described, the combination of a fluid pressure controlling

2

cylinder, a piston movable therein, and means for supplying fluid pressure to said cylinder, said cylinder having a main piston guiding portion and an enlarged portion at the upper end of said main guiding portion, said enlarged portion forming a condensation receiving chamber provided with a channel draining to an outlet, the capacity of said chamber being as great as the capacity of the chamber within the main piston guiding portion between the top of said main guiding portion and the upper face of the piston when said piston is in its lowermost position.

10 3. In a device of the class described, the combination of a fluid pressure controlling cylinder, a piston movable therein, and means for supplying fluid pressure to said cylinder, said cylinder having a main piston guiding portion and an enlarged portion at the upper end of said main guiding portion, said enlarged portion being provided with an effectively closed head and forming a condensation receiving chamber, the capacity of said chamber being as great 25 as the capacity of the chamber within the main piston guiding portion between the top of said main guiding portion and the upper face of the piston when said piston is in its lowermost position.

15 30

In testimony whereof I hereby affix my signature.

CHARLES E. WAREAM.
